UNITED STATES PATENT OFFICE.

PETER HLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

THREAD-CUTTING MECHANISM FOR SEWING MACHINES.

Application filed July 1, 1920. Serial No. 293,351.

To all whom it may concern:

Be it known that I, PETER HLEB, a citizen of the United States, residing at Elizabeth, in the county of Union and State of New Jersey, have invented certain new and useful Improvements in Thread-Cutting Mechanisms for Sewing Machines, of which the following is a specification, reference being had therein to the accompanying drawings.

5 This invention relates to a thread-nipper and cutter and particularly to such a nipper and cutter as employed in connection with a rotary hook in a cylinder arm barring and tacking or button-sewing machine.

10 An object of the invention is to provide a simple and easily assembled arrangement of the thread-detaining and severing means on the throat-plate and one that will require very little space transverse the work-arm so that it may be applied to narrow work-arms and still may be so located with respect to the loop-taker as not to interfere with the removal and insertion of the lower thread mass.

15 In the preferred embodiment of the invention the thread-detaining and severing means is mounted on a support pivoted so that it may be oscillated on the under side of the throat-plate. This throat-plate forms the entire upper surface of the free outer end of the hollow work-arm and also carries an operating lever fulcrumed thereon intermediate its ends outwardly of the pivot for the thread-detaining and severing means. 20 One end of the lever has a link connection with the pivoted support while the other end has detachable link connection with a bar extending through and longitudinally of the hollow arm to the stop-motion mechanism for the machine.

25 All the parts when assembled are within the confines of the work-arm and the whole thread-detaining and severing means may be detached from the work-arm with the throat-plate after the detachable link connection between the bar and the lever is disconnected. This allows ready removal of the thread-detaining and severing means for inspection, adjustment and repair, and also 30 allows assembling thereof on the throat-plate before it is applied to the work-arm.

35 Referring to the accompanying drawings illustrating the preferred embodiment of my invention, Fig. 1 is a rear side elevation of the machine. Fig. 2 is a bottom plan view.

Fig. 3 is a bottom plan view on an enlarged scale of the throat-plate removed with my thread-severing and detaining means assembled thereon. Fig. 4 is a detail perspective view of the ledger-blade and Fig. 5 is a detail perspective view of the bobbin-thread pull-off and shear-blade.

40 The machine frame comprises a standard 1 provided with a horizontally extending hollow work-arm 2 spaced above the base 60 thereof. The frame also has an overhanging bracket-arm 3 in the head 4 of which the needle-bar 5 carrying the needle 6 is mounted to reciprocate in a well known manner. Within the arm 3 is mounted the main driv- 65 ing shaft 7 provided at the rear end with loose and tight pulleys 8 and 9, respectively, the tight pulley 9 being provided with a stopping cam having a stop-lug 10. Upon the shaft 7 within the arm 3 is a bevel-gear 70 11 meshing with a gear 12 upon a vertical shaft 13 provided at its lower end with a second bevel-gear 14 meshing with a bevel-gear 15 on the loop-taker shaft 16 extending 75 through the hollow work-arm to the rotary 80 hook 17 which is fixedly mounted on the shaft 16. The gears 11, 12, 14 and 15 are so proportioned as to give a two-to-one rotation to the loop-taker shaft, the shaft 16 having 85 two revolutions to one of the shaft 7.

90 The standard 1 is provided with a transversely extending shaft 18 on which is mounted the cam-disk 19. This disk is operated from the main-shaft 7 by means of a worm 20 meshing with a worm-wheel 21 on the shaft 18. From the cam-disk 19 various movements are imparted to the work-holder, stop mechanism and the thread-cutter as will presently be described.

95 Mounted for jogging and reciprocating movement upon the hollow work-arm is a work-support 22 and button-clamp 23 both secured to the block 24. The work-support and button-clamp are given movements transverse the work-arm by means of the 100 bellcrank 25 fulcrumed on the base at 26, connected to the lower end of the lever 27 by means of a link 28, the lever 27 being fulcrumed at 29 in a bracket 30 secured to the frame of the machine. The lever 27 is 105 rocked through a cam-follower 31 upon the upper end thereof which works in a suitably shaped cam-groove 32 in the cam-disk 19. Movements longitudinally of the work-arm are imparted to the work-support 22 and the 110

button-clamp 23 by means of a second lever and suitable cam (not shown) mounted on the opposite side of the bracket-arm 3. The work-support, button-clamp and the means 5 for imparting jogging movements thereto are substantially those disclosed in the patents to Sullivan No. 777,564, of December 13, 1904 and Barron No. 1,093,241 of April 14, 1914.

10 A stop-lever 33 is pivoted in the frame at 34 and is provided at its upper end with a belt-shift 35. Also mounted in the upper end of this lever is a spring-pressed plunger 36 adapted to cooperate with the stopping cam and the stop-lug 10 thereon. The stop-lever 33 also has a limited sidewise or overthrow movement on the frame because of a pivot connection at 37. Connected to the lower end of the stop-lever is a spring 20 38 secured at the opposite end to a pin 39 on the base of the machine, said spring tending to pull the stop-lever into stopping position as shown in Fig. 1. Mounted upon the frame and adapted to be released by 25 means of a lug, not shown, on the rear of the cam-disk 19 is a spring-pressed latch 40 which retains the stop-lever in inoperative position holding the driving belt on the tight pulley 9.

30 The thread-detaining and cutting mechanism is mounted upon the under side of the throat-plate 41 which, in the embodiment shown, is substantially the same width as the top of the work-arm 2 and forms the 35 outer upper surface thereof. Secured to the under side of this throat-plate is a downwardly extending supporting bracket 42 and pivotally supported between the free end 43 of this bracket and the throat-plate is a supporting arm 44 upon which is mounted the thread-cutting and holding means. A needle-loop detaining and bobbin-thread pull-off blade 45, together with a flat yielding bobbin-thread-nipper-blade 46 is secured to 40 the supporting arm 44 by means of a screw 47. Also secured to the supporting arm 44 is a flat barbed plate 48. The needle-loop detaining and bobbin-thread pull-off blade 45 is provided with an upwardly extending 45 inclined shear blade 49, as shown in Fig. 5, said shear-blade cooperating with a ledger-blade 50 secured to the under side of the throat-plate by means of a screw 51. The ledger-blade has a limited adjustment upon 50 the throat-plate because of the elongated opening 52 therein through which the screw 51 extends. The free end of the needle-loop detaining and bobbin-thread pull-off blade 45 has frictional engagement when operated 55 with the surface of a spring-plate 53 which prevents the detained needle-loop from falling off. Fulcrumed intermediate its ends at 54' to the throat-plate on the opposite side of the pivot for the supporting arm 44 60 from the needle and the loop-taker is a lever

54 having connection at one end by means of a link 55 with the supporting arm 44 at point 56. The opposite end 57 of said lever has link connection 58 with the draw-bar 59, said draw-bar being mounted so as to reciprocate within a groove 60 formed in a wall of the hollow work-arm 2 but does not project beyond the outer surface thereof, the bar being retained in said groove by means of a plate 60' secured to the wall of the 70 work-arm in any desirable manner, preferably by screws as shown in Fig. 1. The under side of the throat-plate 41 is provided with a recess 61 into which the free end of the shear-blade 49 extends. 80

The draw-bar 59 is connected at its rear end with a block 62 provided with a recess 63 into which extends the lower end 64 of the lever 65 fulcrumed at 66 in a bracket 67 secured to the machine frame, the upper end 85 of the lever 65 being provided with a cam-follower fitting in a cam-groove 68 in the cam-disk 19. The block 62 is also provided with a roller-stud 69 embraced by the forked end of a bellcrank-lever 70 fulcrumed at 71 90 to the machine. On the other arm of the bellcrank 70 is a spring-pressed plunger 72 urged to its outer position by the spring 73. The lower end of the stop-lever 33 is provided with a recess into which the plunger 95 72 is forced by the spring 73 when the bellcrank-lever 70 is moved to bring said plunger in alinement with said recess.

Pivottally mounted by means of the bracket 74 on the base of the frame is a 100 lever 75 which may be connected to any suitable treadle mechanism, not shown. The lever 75 is adapted to reciprocate a plunger-rod 76 against the action of a spring 77, the end of the plunger-rod 78 being adapted to abut against the lower end of the stop-lever 33 to force this lever into running position. The stop mechanism and the means for operating the cutting and nipping mechanism therefrom are substantially those disclosed 110 in the patent to Barron, No. 1,093,241, before mentioned.

The loop-taker 17, as disclosed, is of the rotary hook type and is rotated constantly 115 in the same direction. It is a peculiarity of this type of loop-taker that it does not pass bodily through the needle-loop but carries the loop around the lower thread mass, giving the needle-loop a half twist in such carriage so that the work-limb of the needle-loop is closely adjacent the lower thread immediately under the work and therefore both the lower thread and the work-limb of the needle-loop are separated from the supply limb of the needle-loop and may be 125 seized and severed simultaneously by a single shear cut of the shear-blade 49 upon operation of the thread-cutter at the proper time. In the present arrangement of the device the bobbin - case - position - finger- 130

bracket 79 is secured to the vertical end wall of the hollow work-arm 2 by means of the screw 80.

After the loop-taker and its operating mechanism is assembled within the work-arm the lower open side of this arm is closed by means of a curved cover 81 which is provided with oppositely extending ribs 82 slidable in grooves formed in the work-arm 10 so that said cover 81 may be readily slid into place or removed to expose the mechanism. The thread-detaining and cutting means is enclosed by means of a cap 83 hinged at the point 84 to the cover 81.

15 It will be noted that none of the elements of the thread-nipper and cutter or its operating mechanism extend beyond the walls of the hollow work-arm but occupy very little space transverse of this arm. It is 20 therefore unnecessary to widen the arm to accommodate this thread-nipper and cutter with its cutting mechanism, thus allowing the use of a very narrow work-arm. If it is desired to have a flat bed machine a 25 cloth-plate 85 may be secured thereto, in the embodiment shown, by means of blocks 86, 87, adapted to extend into short recesses 88, 89, cut into the outer surface of the work-arm.

30 In operation at the beginning of a stitching cycle the bell crank-lever 75 is depressed by means of the foot-treadle and through the slidable rod 76 the lower end of the stop-lever 33 is forced outwardly shifting the belt from the loose pulley 8 to the tight pulley 9 and removing the plunger 36 from alinement with the stop-lug 10. Upon the first reciprocation of the needle 6 the loose end of needle-thread is drawn through the 35 work to the under side of the throat-plate by the rotating hook 17. At this time the cam-follower on the upper end of lever 65 rides off the raised portion 68' onto the dwell 68'', slightly retracting the nipper 48 and also the nipper 46 and the needle-loop detaining and bobbin-thread pull-off blade 45. The retraction of the barbed portion of the nipper 48 across the needle-opening shown at 41' in Fig. 3, detains the free end of the 40 needle-thread against the under side of the throat-plate, the bobbin-thread being held by the nipper 46. At the end of the forth stitch the cam-follower on lever 65 moves into the long dwell 68''', further retracting the nipper and releasing the bobbin-thread and also the needle-thread, sufficient 45 stitching having been made to prevent unravelling.

The stitching then proceeds in the usual manner and at the end of the stitching operation the needle makes several stitches in the same hole to act as tying stitches. As the needle goes down on the last reciprocation the catch 40 is released by a lug, not shown, on the surface of the cam-disk 19,

releasing the stop-lever 33 which, under the action of the spring 38, shifts the belt to the loose pulley 8 and moves the plunger 36 into alinement with the stop-lug 10. The main-shaft continues to turn due to its momentum, the needle rises and as its loop is cast off the thread-cutter advances and the loop-detainer 45 pulls off the bobbin-thread and enters the loop. The advance of the thread-cutter and detainer is caused by the follower on the lever 65 riding up on the raised portion 68' of the cam-groove 68. The bellcrank-lever 70, being also connected to the lever 65, is shifted, bringing the plunger 72 into alinement with the recess 80 in the lower end of the stop-lever 33 just before the stop-lug 10 comes in contact with the plunger 36. Then as the lever 33 is given its sidewise or overthrow movement by the momentum of the shaft the bellcrank 70 is oscillated, and through the roller-stud 69 and draw-bar 59 the thread-cutter and detainer means is given its final movement, nipping the bobbin-thread beneath the spring-plate 46 and severing this bobbin-thread and the work-limb of the needle-loop between the cutting edges 49 and 50. The lever 65 is allowed this extra movement because the cam-groove 68 is enlarged opposite the raised portion 68'.

It will be noted from an inspection of Figs. 1 and 3 that the thread-detaining and nipping means with its operating mechanism is mounted on the under side of the throat-plate and at no point do they extend beyond the edges thereof. Therefore in order to remove them as an entirety from the machine all that is necessary is to disconnect the detachable connection at 58' and remove the throat-plate. This allows easy access to the thread-detaining and severing device for inspection, adjustment and repair, and also allows complete assemblage thereof on the throat-plate before insertion in the machine. If it is desired to use the machine without the throat-detaining and severing means, all that is necessary is to remove the throat-plate with this mechanism assembled thereon and insert in place thereof a throat-plate without this mechanism.

Although the device is illustrated and described as employed with a rotary hook, it is clear that it is not confined to use with this type of loop-taker in all aspects of the invention but in certain aspects may be used with any other type of loop-taker desired.

Having thus set forth the nature of the invention, what I claim herein is:—

1. In a sewing machine having stitch-forming mechanism, a removable throat-plate, a thread-detaining and severing means movably mounted on the under side of the throat-plate, a lever fulcrumed on said throat-plate, a link connection from said

- lever to the thread-detaining and severing means, operating means, and a detachable link connection between said lever and the operating means.
5. In a sewing machine, in combination, a frame having a hollow work-arm extending therefrom, stitch-forming mechanism including a reciprocating needle and a loop-taker cooperating therewith, stop-motion mechanism for the stitch-forming mechanism, a detachable throat-plate adjacent the free end of the work-arm, a thread-detaining and severing means pivotally mounted on the under side of the throat-plate, a lever fulcrumed on said throat-plate having a link connection for operating the thread-detaining and severing means, a second link connected to said lever, said thread-detaining and severing means, lever and links all confined within the outer walls of the hollow work-arm and an operating means within said arm having connection with the stop-motion mechanism and detachably connected with said second link. 50
6. In a sewing machine for separate stitching operations, in combination, a frame provided with a hollow work-arm extending horizontally therefrom, stitch-forming mechanism comprising a reciprocating needle and a lower-thread loop-taker mounted to rotate continuously in the same direction within the hollow work-arm and adapted to cooperate with the needle to form stitches, a throat-plate, a thread-severing and detaining means mounted to operate on the under side of the throat-plate and adapted to cut the lower thread and the work-limb of the needle-loop simultaneously at the end of a stitching operation, a lever pivoted to the under side of the throat-plate and adapted to operate the thread-detaining and severing means, a link pivoted to the lever, a stop-motion mechanism for the stitch-forming mechanism, and a bar located within the periphery of the work-arm connected to said link and to said stop-mechanism whereby the thread-detaining and severing means is operated by said stop mechanism. 55 60 65 70 75 80 85 90 95
3. A sewing machine having a frame including a hollow work-arm free of support at one end and at its other end joining the main frame of the machine above the base of the latter so as to afford free space under said arm, stitch-forming mechanism incorporated in said frame, thread-severing means movably mounted to cut the thread on the under side of the work, means for operating said thread-severing means comprising a lever fulcrumed intermediate its ends at the free end of the work-arm, a link pivotally connected at one end to said lever and at its opposite end to said thread-severing means, operating means, and a second link pivotally connected at its opposite ends, respectively, to said lever and said operating means.
4. In a sewing machine, in combination, a frame having a hollow work-arm extending therefrom, stitch-forming mechanism including a reciprocating needle and a loop-taker cooperating therewith, a detachable throat-plate, a thread-detaining and severing means movably mounted on the under side of the throat-plate, a lever fulcrumed intermediate its ends on the throat-plate and having link connection at one end to said thread-detaining and severing means, a stop-motion mechanism for the stitching mechanism, and a link connection from the other end of the lever to the stop-motion mechanism. 40 45

In testimony whereof, I have signed my name to this specification.

PETER HLEB.
